UNITED STATES PATENT OFFICE.

DENNIS O'B. LADD, OF CHICAGO, ILLINOIS, ASSIGNOR OF ONE-HALF TO
GEORGE FARNSWORTH, OF SAME PLACE.

SLIDE-VALVE.

SPECIFICATION forming part of Letters Patent No. 331,506, dated December 1, 1885.

Application filed March 30, 1885. Serial No. 160,557. (No model.)

To all whom it may concern:

Be it known that I, DENNIS O'B. LADD, a citizen of the United States, residing at Chicago, in the county of Cook and State of Illinois, have invented certain new and useful Improvements in Slide-Valve Mechanism for Steam-Engines, of which I do declare the following to be a full, clear, and exact description, reference being had to the accompanying drawings, forming part of this specification.

My present invention has relation to the improvement of that class of steam-engines wherein the main or driving piston is controlled by a slide-valve so constructed—that is to say, provided with "lap"—that it will admit steam to the main cylinder during a portion only of the piston-stroke, the steam so admitted causing, by reason of its expansion, the completion of the piston stroke. In the usual form of valves of this class the construction is such that one and the same movement of the valve determines proportionately both the period of admission and exhaust of the steam to and from the main cylinder, so that if the valve be given a very short stroke, in order to cut the steam off "short," the period during which the exhaust-port of the main cylinder will be opened and steam can escape therefrom will be correspondingly lessened. Hence the force of the expansive steam upon the induction side of the main piston will be resisted by the confined steam and air upon the exhaust side of the piston, which is unable to escape by reason of the exhaust-port being closed.

It is a fact well recognized in steam engineering that, in order to obtain the most effective work from the engine, it is of the utmost importance that the "back-pressure" in the cylinder—that is to say, the resistance on the exhaust side of the piston—should be reduced to the lowest degree possible, for the reason that all back-pressure not only diminishes the efficiency of the engine but is also a total loss of energy. The most satisfactory results are obtained, therefore, when the indicator-card of the diagram of the engine shows the line of back-pressure approximating as closely as possible to the atmospheric line, or, in other words, shows a practical absence of back-

pressure. In working engines at a very high rate of speed the steam is usually cut off very short, and it is, therefore, in such cases that the loss incident to back-pressure is most seriously encountered.

My present invention has for its object to provide a slide-valve of such improved construction that a uniform free exhaust from the main cylinder may be obtained during both the direct and expansive action of the steam, and that the back-pressure incident to the usual closing of the exhaust during such period may be avoided.

To this end my invention consists, primarily, in a slide-valve having escape-ports therein, and provided with suitable supplemental valve mechanism for opening and closing said escape-ports in such manner that there will be a free exhaust from the main cylinder during the time that the steam therein is acting both directly and expansively.

My invention also consists in various novel features of construction hereinafter described, illustrated in the accompanying drawings, and particularly defined in the claims at the end of the specification.

Figure 1 is a perspective view of my improved slide-valve, showing one side thereof detached. Fig. 2 is a view in side elevation. Fig. 3 is a view in central vertical section. Fig. 4 is a view in horizontal section on line *x* *x* of Fig. 2. Fig. 5 is a detail fractional view in vertical section on line *y* *y* of Fig. 2. Fig. 6 is a view in central horizontal section on reduced scale, showing my improved valve as applied to the cylinder of an engine. Fig. 7 is a detail perspective view of what I term the "supplemental piston" and the "equalizing-bar." Fig. 8 is a detail perspective view from the back side of what I have termed the "supplemental valve." Fig. 9 is a detail perspective view of what is termed the "auxiliary valve." Fig. 10 is a view on reduced scale in side elevation, showing the position of the slide-valve within the steam-chest, and showing the means for adjusting the auxiliary valve.

A designates the main body of the slide-valve, which is suitably attached, as by the nut *w*, to the usual valve-rod, *W*, and consists

of a hollow or chambered casting provided with an exhaust-cavity, a , upon either side whereof are the escape-ports B and B' , which correspond in length to the ports of the steamways c c' of the main cylinder C , although somewhat narrower than such ports. The exhaust-cavity a is preferably cut away at its back, as shown, to decrease the friction-surface of the supplemental valve-seat. In the upper 10 and lower parts of the slide-valve between the escape-ports B and B' , and communicating with the chamber of the slide-valve, are formed, respectively, the escape-ports B^2 and B^3 , which communicate with the exhaust-port c^2 of the main cylinder, and serve to deliver 15 exhaust-steam thereto from the escape-ports B and B' of the slide-valve. Within the chamber A^2 of the main slide-valve is placed the supplemental valve D , the face of which bears 20 upon the seat back of the exhaust-cavity a , and is adapted to alternately open and close the escape-ports B B' . This supplemental valve D , as particularly seen in Figs. 3 and 8, is preferably formed of different thicknesses, 25 the thinnest portions at the top and bottom being held between the cross-bars E and E' , the ends of which rest within the grooves e in the wall of the valve. The cross-bars E and E' are held in place by means of the back plate A^3 , through the bolt-holes a^3 of which suitable 30 bolts, a^3 , will pass into the holes a^4 of the slide-valve wall. Upon the back plate A are formed the lugs a^5 , through which pass the set-screws a^6 , that bear upon the cross-bars E 35 and E' , and allow the same to be adjusted to compensate for wear. The central portion of the cross-bar E is cutaway, as shown, to allow free egress of the exhaust-steam from the escape-ports B and B' and chamber A^2 into the 40 escape-port B^2 . Upon the back of the supplemental valve D is formed the stud d , and around this stud fits the squared washer d' , that enters the squared opening in the equalizing-bar F , the lower end of which is ful- 45 crumed in the socket e^3 of the cross-bar E' , and the upper end is formed with segmental rack-bar f , which engages with the rack-bar g of supplemental piston-valve G , by which the supplemental valve is moved, as will presently 50 appear. The equalizing-bar is held in place upon the stud d by means of the clamp-plate I^3 , which is connected to the shouldered lugs d^2 and d^3 of the supplemental valve by means of suitable dowel-pins.

55 My purpose in connecting the supplemental valve D with its operating-piston G by means of the equalizing-bar F is to enable movement to be imparted to this valve from a central point, so that greater freedom and evenness 60 of movement and less friction will result than would be the case were the piston connected directly to the valve near its top.

About the center of the back plate A^3 of the slide-valve an opening is formed of an area, 65 preferably, somewhat greater than the area of either of the escape-ports B or B' , and within

this opening is fitted the pressure-plug H , formed of the plates h h' , with intermediate washer-rings united by the screw h^2 , or in other suitable manner. The function of this 70 pressure-plug is to hold the supplemental valve D snugly against its seat and compensate for any wear of parts, and this it will accomplish by reason of the inward pressure upon it of the live steam within the steam-chest. 75

From the construction of parts as thus far defined, and by reference to Fig. 6, wherein the position of my improved valve with respect to the main cylinder is shown, it will be apparent that when steam is being admitted to the main cylinder through one of the steamways, as c , the exhaust-steam and air upon the exhaust side of the piston can pass freely through the steamway c' , escape-port B' , 80 chamber A^2 , and ports B and B^3 into the exhaust-cavity a of the slide-valve, whence it will discharge freely into the open air. This discharge of the exhaust-steam and air through the steamway c' and escape-port B' continues 85 until approximately the end of the piston-stroke, so that during the forward movement of the piston there will be no confinement of the steam and air on the exhaust side, and consequently no back-pressure to resist the 90 movement of the piston. At the end of the forward stroke of the piston, when the exhaust is practically complete, the supplemental valve D will be forced to close the escape-port B' , and the preferred mechanism by which 95 this movement of the supplemental valve can be effected will next be described.

The piston G , connected with the equalizing-bar F , has its ends sustained, respectively, 100 within the cylinders K and K' , formed in the wall of the slide-valve A , and both of these cylinders and their connections are in all respects alike. For convenience of construction and replacement of parts, the slide-valve A is formed with the threaded portions a^7 at its 105 ends, over which portions fit the screw-caps L , that form the ends of the cylinders K K' . From the top of these cylinders extend the steam-channels k k' , which, as shown in Fig. 2, terminate in the ports in the groove or way M , 110 wherein works the auxiliary valve N as the slide-valve is moved to and fro within the steam-chest. This auxiliary valve is provided at its top with a loop, n , or other suitable means, whereby it is fixed in a manner permitting 115 slight lateral play on the auxiliary valve stem O , the ends of which are held respectively within a stuffing-box, o , and threaded perforation o' in opposite side of the steam-chest, so that by means of the hand-wheel o^2 the position of the auxiliary valve may be readily adjusted for the purpose of equalizing the exhaust action 120 at each part of the stroke. The body of the auxiliary valve is hollow, as seen in Fig. 9, and is provided with the end escape-ports, n' 125 n^2 , adapted to be brought respectively coincident to the ports of the steam-channels k and 130

k', and is provided also with the long central escape-port, *n*³, which in the various positions of the auxiliary valve with respect to the slide-valve will be held above the escape-port *a*³, that is in free communication with the escape-port *B*³ in the upper portion of the slide-valve, as seen in Fig. 3. Each of steam-channels *k* and *k'*, at a slight distance above the cylinders *K K'*, is connected with a cross-channel, *p*, 5 which leads therefrom to the space *p'* of the cushion-valve *P*. The cushion-valves *P* and *P'* are provided at their outer ends with stems *p*², which project through the caps *L*, and the diameter of these stems is so much smaller 10 than the diameter of the channels *p* that when either of these steam-channels is open for the ingress of live steam, the corresponding cushion-valve will be forced outward, as shown at the left-hand side of Fig. 2. The space *p'* of 15 each of the cushion-valves *P* and *P'* communicates with the cylinders *K K'* by means of the short channels *p*³, and in each end of the piston *G* is formed an angular channel, *g*', the rear part of which is adapted to coincide with 20 the steam-channel *k*, as seen at the right-hand side of Fig. 2.

From the foregoing description the operation of my improved slide-valve will be seen to be as follows: Assume the parts to be in 25 the position shown in Fig. 6, the main piston being at the beginning of its forward stroke, at this instant the relative position of the slide-valve and the auxiliary valve *N* is such that the upper port of the channel *k'* has just 30 been uncovered, and the steam entering by this channel and the channels *p* and *g*', has forced the cushion-plug *P'* outward, and has forced backward the supplemental piston *G*, thus causing it to move the supplemental valve 35 *D* over the escape-port *B* of the main valve. Live steam is now being admitted from steam-chest *A*⁴ through the steamway *c* of the main cylinder, and the exhaust-steam is escaping freely from the main cylinder through the 40 steamway *c'* into the escape-port *B'* of the slide-valve, and thence into the chamber *A*² of the valve, and through the upper and lower escape-ports, *B*² and *B*³, (see Fig. 3,) into the exhaust-port *c*² of the main cylinder. Steam 45 thus continues to exhaust through the steamway *c'* and escape-port *B'* not only while live steam is entering through the steamway *c*, but also after the slide-valve has cut off the steam from the way *c*, so that the steam is working 50 expansively, and until on the return movement of the slide-valve the escape-port *B* of this valve is about opposite the steamway *c*. It is when the slide-valve is working with a 55 very short stroke that the entire exhaust will 60 thus occur through the escape-port *B'*; but it will be readily seen that if the slide-valve is working with a long stroke, the first part of the exhaust will occur through the steamway *c'* and escape-port *B'* and the last part of the 65 exhaust through the steamway *c'* and the usual exhaust-cavity, *a*, and exhaust-port *c*². When

on the return movement of the slide-valve the escape-port *B* is thus about opposite the steamway *c*, the position of the slide-valve with reference to the auxiliary valve *N* will be such— 70 that is to say, so far to the right of the center of the slide-valve—that the upper port of the channel *k* will be uncovered so as to admit live steam, and at the same time the upper port of the channel *k'* will for an instant coincide with the escape-port *n*² of the auxiliary valve *N*, so as to permit the steam to escape from the cylinder of the supplemental piston. It will thus be seen that the live steam entering the channel *k* will force the supplemental 80 piston *G* backward and cause it to so move the supplemental valve *D* as to uncover the escape-port *B* of the main slide-valve, and allow the exhaust to escape through said port into the chamber *A*² and escape-ports *B*² *B*³ 85 leading therefrom, while at the same time live steam is entering the main cylinder *C* through the steamway *c'* and is working expansively within the cylinder.

Referring to Fig. 2, and assuming the parts 90 to be in the position there shown, it will be readily understood that if the main slide-valve be moved to the right a sufficient distance to uncover the upper port of the channel *k'* and admit live steam thereto, and at the 95 same time bring the upper port of the channel *k* for an instant beneath the escape port *n*² of the auxiliary valve *N*, the pressure of steam upon the stem *p* of the cushion-valve *P* would force this valve inward, thereby closing the 100 channel *p*³. At the same time live steam entering the channel *k'* would force the cushion-valve *P'* outward, thereby uncovering the channel *p*³ beneath said valve, and by passing through the channel *g*' in the end of the piston *G* would 105 give an initial backward movement to the piston. The piston *G* as it passed the channel *k* would be cushioned by the steam confined between such channel and the cap *L* of the cylinder, since by reason of the closing of 110 the cushion-valve *P* the steam could not escape through the channel *p*³. This cushioning of the supplemental piston is of importance, as it avoids all danger of the piston hammering out the ends of its cylinders. 115

From the foregoing description it will be seen that by my improved construction of slide-valve a free and uniform exhaust is obtained from the main cylinder during the period that the piston is working both by the 120 direct and expansive action of the steam, so that all loss of energy and constant increase and cost of running the engine incident to back-pressure is entirely avoided. The advantages due to my invention are so obvious 125 as to need no further elaboration.

It will be readily understood that the precise details of construction above described may be varied within wide limits without departing from the spirit and scope of my invention. Thus for example the supplemental valve and piston may be connected directly 130

together instead of by an equalizing-bar, the arrangement of steam channel may be varied, and certain features of the invention may be employed without using the invention entire.

5 Having thus described my invention, what I claim as new, and desire to secure by Letters Patent, is—

1. The combination, with a cylinder having suitable steamways, of a main slide-valve 10 having escape-ports therein adapted to be brought coincident with said steamways, and having a supplemental valve adapted to open and close the escape-ports of the slide-valve, said slide-valve and supplemental valve being 15 arranged for relative co-operation, substantially in the manner and for the purpose described.

2. The combination, with a cylinder having suitable steamways, of a chambered slide-valve having escape-ports therein adapted to be brought coincident with said steamways, and a supplemental valve placed within the slide-valve and adapted to open and close the escape-ports thereof, substantially as de- 25 scribed.

3. The combination, with a cylinder having suitable steamways, of a main slide-valve having escape-ports therein, a supplemental valve for opening and closing the slide-valve ports, 30 and a supplemental piston and an auxiliary valve for controlling the movement of the supplemental valve, said several parts being relatively arranged for co-operation substantially in the manner and for the purpose set forth.

35 4. The combination, with a cylinder having suitable steamways, of a slide-valve having es-

cape-ports therein, a supplemental valve for opening and closing the said escape-ports, a supplemental piston in connection with said supplemental valves, an auxiliary valve for said piston, and an adjustable rod for said auxiliary valve, substantially as described. 40

5. The combination, with a cylinder having suitable steamways, of a slide-valve having escape-ports therein, a supplemental valve located within the slide-valve for opening and closing its escape-ports, and a pressure-plug in the wall of said slide-valve adapted to hold the supplemental valve to its seat, substantially as described. 45

6. The combination, with a cylinder having suitable steamways, of a slide-valve having escape-ports therein, a supplemental valve for opening and closing said escape-ports, a supplemental piston in connection with the supplemental valve, an auxiliary valve for said piston and cushion-plugs for the said piston, the various parts being provided with suitable steam-channels, substantially as de- 55 scribed. 60

7. The combination, with a cylinder provided with suitable steamways, of a slide-valve having escape-ports therein, a supplemental valve for opening and closing said escape-ports, a supplemental piston for operating the supplemental valve, and a pivotal link connecting said supplemental valve and piston, substantially as described. 65
